UNITED STATES PATENT OFFICE.

WILLIAM C. McKEOWN, OF BALTIMORE, MARYLAND, ASSIGNOR TO MODERN HOUSE-HOLD APPLIANCE COMPANY, OF BALTIMORE, MARYLAND, A CORPORATION OF MARYLAND.

DISCHARGE MANIFOLD FOR PRESSURE CONTAINERS.

Application filed December 4, 1925. Serial No. 73,146.

My invention relates to discharge manifolds for pressure containers. The principal object of my invention is to devise a discharge manifold that is adapted for use with containers carrying fluid under pressure, that can be readily mounted by inexperienced persons in said containers with the obtention of a sealed joint and that is provided with means for opening the valve that normally closes the entrance to said container.

My invention is more particularly directed towards providing a discharge manifold for use in connection with the tank illustrated and described in my copending application for a liquid fuel gas range, Serial No. 38,481, filed June 20, 1925. The fuel for these ranges consists of a natural gas product which is compressed into a liquid state and distributed to consumers in containers. Hence, there must be some device interposed between the range and the container that will render available for the former the fuel that is present in the latter.

As the containers must be refilled at some central point from time to time, the device above noted must be characterized by a facility in attaching and detaching the same to and from the container. In addition and in view of the fact that such utensils are normally operated by inexperienced persons, the device must possess a capacity for uniformly establishing a gas tight joint with the container in order to reduce the hazard of asphyxiation.

My improved discharge manifold has been designed to meet the foregoing requirements and comprises in a single structure, not only means for unseating the valve with which containers of the type are usually provided, but also is arranged to be readily mounted in the tank with an assurance that a gas tight joint is always provided. The construction is of such a character that the latter condition remains constantly obtainable even though the manifold may be subjected to considerable wear, or the parts be in slight misalignment.

These and other objects are set forth in the following specification, reference being had to the accompanying drawing, and the novel means by which said objects are effectuated will be definitely pointed out in the claims.

In the drawing:

55

Fig. 1 is a sectional elevation of my improved discharge manifold showing the same attached to a typical container.

Fig. 2 is a section along the line 2—2 in Fig. 1, looking in the direction of the arrows.

Fig. 3 is a section along the line 3—3 in Fig. 1, but showing only the lower portion of the manifold.

Fig. 4 is a sectional elevation of the lower portion of my improved manifold.

In the drawing:

65

The numeral 10 represents a container generally having a threaded opening 11, in which is mounted a filling plug 12. A suitable washer 13 may be interposed between said container and plug in order to obtain a sealed connection at this point.

A threaded hole 14 extends inwardly through the plug 12 for any desired distance and an extension 15 is provided on the inner side of said plug, said extension projecting within the interior of the container 10. The extension 15 is provided with a hole 16 having a threaded portion in which is mounted a hollow plug 17. The holes 14 and 16 are axially aligned and extend toward each other to merge into the passage 18 which is of less diameter than either of the aforementioned holes.

85

The junction of the passage 18 with the hole 16 forms a valve seat 19 and the junction of said passage with the hole 14 forms a valve seat 20. A ball 21 normally contacts with the seat 19 through the action of a spring 22 which is interposed between the plug 17 and a platform 23 on which said ball rests.

90

The elements heretofore described are intended to be indicative of a container having a normally closed passage which serves as an entrance thereto. In filling said containers the ball 21, or such other valve as may be desired, is retracted from engagement with the seat 19 and upon the completion of this operation, said ball is returned to its normal position through the action of the spring 22 and the pressure of the contained fluid. The container therefore is provided with adequate means for reducing leakage to a minimum. Pending delivery to the consumer, the hole 14 may be closed by any suitable plug.

100

105

It is the function of my improved discharge manifold to render available the fluids, whether gaseous or liquid, that are carried by the container 10 and to achieve 5 this result by an apparatus having the advantages hereinbefore explained. This device will now be described.

The discharge manifold comprises a body 24 having the threaded portions 25 and 26 10 which are disposed respectively at the lower and upper ends of said body as viewed in Fig. 1. The lower threaded portion 25 is adapted to be inserted in the threaded hole 14.

15 An exhaust duct 27 is provided in the body 24 and extends from the lower end of the portion 25 upwardly through said body to a point beyond a threaded hole 28 which enters said body from one side thereof. A 20 supply pipe 29 is mounted in the hole 28, thereby connecting a duct 27 with any suitable outlet. Above the hole 28, the duct 27 merges into a threaded hole 30 in which is mounted the threaded portion 31 of a 25 valve rod 32. Said rod extends upwardly through a cap 33 which is mounted on the threaded portion 26 and at its upper end carries the hand wheel 34. The portion of 30 said rod which extends through the cap 33 is smooth, as shown in Figure 1 and packing 35 is disposed around said smooth portion in order to obtain a seal at this point of the manifold. The cap 33 carries a ring 36 which is adapted to compress the packing 35 in order to obtain the foregoing result.

Below the threaded portion 31, the valve 40 for the exhaust of such fluids as may be 40 within the container 10.

The reduced portion 37 of the rod 32 extends through a hole provided in a head 38 which is loosely suspended on the end of 45 the threaded portion 25. In order to achieve this construction, the head 38 is recessed on its top side to form the annular flange 39 having a lip 40 which contacts with one side of a groove 41 formed on the lower 50 end of the portion 25. The internal diameter of the aforementioned lip and flange is greater than the diameter of said groove and the flange 42 which forms one wall thereof. Therefore, said head is capable of 55 transverse movement relative to the portion 25 and also, since the depth of the above recess is greater than the thickness of the flange 42, said head is capable of longitudinal movement relative to said portion.

60 In using my improved manifold, the body 24 is mounted in the plug 12 as shown in Fig. 1. During this insertion, it is evident that, owing to the loose mounting of the head 38 on the portion 25, the former will 65 readily adjust itself to obtain a full con-

tact of the beveled surface 43 on said head with the seat 20, thereby securing a perfect seal at this portion of the plug 12 and preventing leakage of the fluid from the container 10 when the valve controlling the 70 entrance thereto is open. Moreover, it is further evident that the above functioning will obtain regardless of the wear on the screw threads of the portion 25, or a slight misalignment of said portion with the hole 75 14. As the head 38 is preferably made of a suitable metal, a positive seal is secured between the manifold and plug 12 which is more effective than would be the case if a fibrous, or other seal of similar character was utilized.

In order to establish a flow through the duct 27, it is only necessary to operate the hand wheel 34 in order to cause the downward movement of the valve rod 32, thereby causing the portion 37 thereof to force the ball 21 away from the seat 19. The flow will then continue until the container is exhausted, or the ball 21 is permitted to return to its normal position.

90 My improved discharge manifold possesses the great advantage of longevity, especially under conditions which require its frequent attachment and detachment to and from pressure containers. As this durability is combined with a facility for always establishing a perfect seal with the containers, it may be associated with, the manifold is of particular desirability under conditions where it is operated by inexperienced persons, such as the domestic ranges to which reference has already been made.

95 While I have shown one set of elements and combinations thereof for carrying into effect my improved manifold, it is to be understood that the same is for the purpose of illustration only and in no wise to restrict my device to the exact structure shown, for many changes may be made therein without departing from the spirit of my invention.

100 I claim:

1. The combination with a container having a passage provided with a valve seat communicating with the interior thereof, of a discharge manifold movably mounted in said passage, and a head attached to one end of said manifold and capable of movement relative thereto, said head having a hole registering with said passage and adapted to effect a sealed joint with said seat through the movement of said manifold.

115 2. The combination with a container having a passage provided with a valve seat communicating with the interior thereof, of a discharge manifold mounted in said passage and a head attached to one end of said manifold and adapted for transverse movement relative thereto, said head having a hole registering with said passage and

adapted for a sealing engagement with said seat when said manifold is mounted in said passage.

3. The combination with a container having a passage provided with a valve seat communicating with the interior thereof, of a discharge manifold movably mounted in said passage and a head, having a hole registering with said passage, loosely suspended on one end of said manifold and adapted for a sealing contact with said seat through the movement of said manifold.

4. The combination with a container having a normally closed passage, provided with a valve seat, communicating with the interior thereof, of a discharge manifold movably mounted in said passage, a head attached to one end of said manifold and adapted for transverse movement relative thereto, said head having a hole registering with said passage and adapted for a sealing engagement with said seat, and means

carried by said manifold for opening said passage.

5. The combination with a container having a normally closed passage, provided with a valve seat, communicating with the interior thereof, of a discharge manifold movably mounted in said passage, a head, having a hole registering with said passage, loosely suspended on one end of said manifold and adapted for a sealing engagement with said seat, and means carried by said manifold for opening said passage.

6. A discharge manifold comprising a body provided with a duct and a sealing head for engagement with a container attached to one end of said body, adapted for transverse movement relative thereto, said head having a hole registering with said duct.

In testimony whereof, I affix my signature.

WILLIAM C. McKEOWN.
